UNITED STATES PATENT OFFICE

2,670,717

SWIVEL CONNECTION FOR HYDRAULIC HOISTS

Raymond Q. Armington, Shaker Heights, Ohio,
assignor to The Euclid Road Machinery Co.,
Cleveland, Ohio, a corporation of Ohio

Application August 27, 1948, Serial No. 46,516

1 Claim. (Cl. 121—46)

1

The invention relates to hydraulic power motors, and more particularly to motors of this type having a cylinder which is pivotally supported or suspended so as to be oscillatable around an axis of oscillation.

An object of the invention is to provide improved means for transmitting fluid power to an oscillatable power cylinder.

A further object of the invention is to provide improved fluid power transmission means suitable for use with an oscillatable cylinder for a fluid power motor, such means avoiding the use of flexible conduit.

A further object of the invention is to provide improved inflexible means of the nature indicated, said means being adapted to supply fluid power to an oscillatable cylinder from a plurality of supply sources through a plurality of conduits.

A further object of the invention is to provide an oscillatable cylinder having an inlet port provided with coupling means, said coupling means being located on the axis of oscillation of the cylinder, and said coupling means receiving fluid power from a conduit, the portion of the conduit next adjacent said coupling means being likewise located on said axis of oscillation.

A further object of the invention is to provide a motor mounting of the type described wherein the mounting of the cylinder for oscillation about an axis is accomplished solely by means of swivel joints in the power fluid inlet and outlet pipes.

Other objects and advantages of the invention will be apparent from the accompanying drawing and description and the essential features will be set forth in the appended claim.

This application is a continuation in part of my copending application Serial No. 578,611, filed February 19, 1945, now Patent No. 2,466,352.

The drawing shows a top plan view of one embodiment of my invention with the hydraulic motor and supply pipe swivel connections broken away in central section to more clearly show the construction.

This invention is applied to a double acting cylinder within which a piston reciprocates and it is contemplated that the piston rod will be attached to a lever or crank which, in its operation, requires the double acting cylinder of my invention to pivot about an axis of oscillation which in the present drawings is indicated by the dot-dash line "A." The present invention provides novel means for supporting the cylinder for this oscillation so as to allow for moder-

ate twist and swaying of the motor cylinder following wear at any of the connecting points without putting undue stress on the fluid connections to the motor which would be apt to cause damage or breakage.

It has been customary to introduce the fluid power to opposed ends of the cylinder through means including certain conduit portions which are sufficiently flexible to permit of cylinder oscillation, and in practice this was often done through rubber hose connections. In certain applications, such as excavating, hoisting, conveying, or grading devices, the work is carried on in all variety of climatic conditions and working hazards, involving the possibility of injury to flexible conduit of the type indicated, and repairs are difficult or inconvenient, or replacement parts may not be conveniently available.

In solving these problems I have devised a substantially permanent assembly for a fluid power motor, wherein oscillation of the cylinder is permitted, but wherein the fluid power transmitting conduit may be formed from rigid, relatively inflexible piping of the kind normally available, by use of a novel mode of arrangement and connection of said piping with respect to the cylinder. This piping is convention metallic conduit and not flexible pipe sections. The objects of the present invention are substantially achieved when connection between said inflexible conduit and said oscillatable cylinder is made at a coupling having complementary parts, one part fixed with respect to the cylinder and the other part fixed with respect to the conduit, one said part being rotatable with respect to the other said part, and the coupling point being located on the axis of oscillation of the cylinder.

In the drawing, I have shown a cylinder 10 in which reciprocates a piston 11 which is provided with a piston rod 12, one end of which 12a is adapted to be connected to a crank or lever or other device to be moved. The fluid motor here shown is of the double acting type, fluid power being admitted alternately to the chambers within cylinder 10 on each side of the piston 11 by valving means not shown. Suitable packing is provided at 13 where the piston rod passes through the cylinder head. Inlet and outlet passageways 14 and 15 are provided at opposite ends of the cylinder so as to make it double acting. The pressure fluid is introduced and exhausted through the metallic conduit pipes 16 and 17. These pipes are free of all fixed support for a distance of the order of several feet 55 from the upper end of cylinder 10 as viewed in

the drawings, but at such a distance each pipe is clamped in a bracket 18 to a fixed portion of the machine.

The mounting of cylinder 10 for oscillation about the axis *a* is solely by means of the swivel connections 19 and 20. These connections are exactly alike and therefore one only will be described. Referring to the swivel connection 19, the nipple 21 is rigid with the pipe 17 and is stationary. The sleeve 22 is integral with the cylinder 10 and oscillates therewith. A snap ring 23 assembled in a suitable groove in nipple 21 engages against a metal washer 24 which is held in position by an annular sealing ring 25 and a collar 26 which is held by stud bolts 27 which are threaded in the suitable openings in the sleeve 22.

The swivel connections 19 and 20 are coaxial on opposite sides of the cylinder 10 and preferably aligned on the diameter of the cylinder.

With the above described construction, the connections to the hydraulic motor are all of standard pipe which is usually available on a construction job and the only other part requiring replacement is the packing ring 25 for which many emergency materials may be used. The construction, however, provides considerable flexibility in the mounting of the cylinder 10 because of the unusual length of the metal pipes 16 and 17 between the brackets 18 and the motor. It should be understood that in the rough type of equipment for which this invention is particularly adapted, fine adjustments are not readily made and cannot be maintained because of dirty and difficult working conditions. The present construction, therefore, has proved to be sturdy and dependable in the field within the limits of the loads capable of being withstood by the pipes 16 and 17.

What I claim is:

In a double acting fluid power motor having a cylinder and a piston reciprocable therein, the combination of a trunnion mounting at one end

of said cylinder providing a pivotal support of said cylinder for oscillation about an axis, said mounting consisting solely of a pair of pressure fluid conducting, thin walled conduits in fluid communication with said cylinder of relatively inflexible material having relatively rotatable swivel connections located on said axis, one of said conduits acting as an inlet for one stroke of said piston and an outlet for the return stroke, the other of said conduits acting as an outlet for said one stroke and as an inlet for said return stroke, said conduits communicating with said cylinder on said axis, there being passages operatively associated with said cylinder and communicating between said conduits and opposite ends of said cylinder respectively, said conduits being free and unsupported close to said mounting other than by their connections with said motor, said conduits having fixed supports spaced several feet from their motor connections, and said conduits between said supports and motor connections being rigid enough to support said motor and flexible enough to compensate for misalignment between said motor and parts connected to said motor piston.

RAYMOND Q. ARMINGTON.
